RIBBON FEEDING AND INKING MECHANISM
FOR TYPING MACHINESGeorge Ernest Pelton, Middleburg, Va., assignor
to Ida S. Pelton, Round Hill, Va.

Application November 12, 1946, Serial No. 709,377

29 Claims. (Cl. 197—171)

1

This invention relates to improvements in typing machines, and particularly to teletype machines, invoicing machines, and bookkeeping machines.

The principal object of the invention is to provide improved inking mechanisms and spooling mechanisms for typing machines.

Another object of the invention is to provide an improved driving means which is operative during the typing operation to rotate independently and in a positive manner both a ribbon inking mechanism and a spool upon which the ribbon is being wound.

Another object of the invention is to provide improved driving mechanisms for the ribbon spools which may be selectively disengaged to permit the spools to rotate freely during the unwinding of the ribbon therefrom in order substantially to reduce the frictional drag upon the typing mechanism.

Another object is to provide a nonabsorbent writing ribbon which cannot act as an ink reservoir and is more wear resistant than prior art ribbons.

One object is to provide an inking mechanism which uses a ball for feeding a thin pigment ink to a non-ink-absorbent ribbon.

Another object is to provide two ink mixing means, one in the reservoir for ink and one in the housing near the reservoir.

Another object of prime importance is to provide a non-ink-absorbent ribbon, which may be 288 yards long, utilizing large horizontally mounted spools; the ribbon being thinner than prior art ribbons, three yards occupying no more space in the spool, than one yard of ordinary standard, cotton typing machine ribbon.

Another object is to get away from the poor writing results secured from twelve yard cotton or silk ribbons which are medium or heavily inked and which are ink-absorbent, the writing appearance changing almost from day to day and soon becoming dim.

Another object is to provide new larger spools mounted in a new, improved manner and much longer ribbon and still maintain very light type-bar action, action of the keys, and light movement for the return of the carriage in hand operated typing machines.

Another object is to provide improved inking mechanisms for teletype machines and electrical typing machines of all kinds and to make it possible to secure greatly improved writing results for the original sheets and for all carbon copies.

Another object is to provide large spools which

2

may be mounted in present typing machines, simply as attachments, with improved inking units of small size, thereby making it possible at much less cost to have an ink fountain typewriter which may be used for years without replacing the new non-ink-absorbent ribbon, and which greatly reduces the ribbon expense.

Other objects of the invention will be apparent from the following description and claims:

- 10 In the accompanying drawings:
Fig. 1 is a top plan view of a portion of a typing machine equipped with the improved mechanisms.
Fig. 2 is a fragmentary top plan view showing the relation between the ribbon inking means, rotatable spool support and driving means therefor.
Fig. 3 is an end elevation of the inking mechanism shown in Figs. 1 and 2.
Fig. 4 is a view showing the inking mechanism in front elevation.
Fig. 5 is a view taken along the line 5—5 of Fig. 4.
Fig. 6 is a sectional view taken along the line 6—6 of Fig. 5.
Fig. 7 is a sectional view taken along the line 7—7 of Fig. 6.
Fig. 8 is a fragmentary sectional view showing a portion of the inking mechanism upon an enlarged scale.
Fig. 9 is a view showing a ribbon spool and its mounting partially in elevation and partially in section.
Fig. 10 is a top plan view of a modified form of spool-mounting with the spool removed.
Fig. 11 is a view taken along the line 11—11 of Fig. 10 with the spool in place.
Fig. 12 is a view showing a hard ball for applying ink.
Fig. 13 is a view showing a ball contacting the ribbon.
Fig. 14 is a view of another form of inking mechanism.
Fig. 15 is a view of another form of inking mechanism.
Fig. 16 is a view of a post of Fig. 15.
This invention may be applied to a teletype machine or to a typewriter, or type mechanism of any kind using an ink transfer member.
In the accompanying drawings, for the purpose of illustrating an embodiment of my invention, it is shown as applied to a type-writing machine 1, having a frame 2, and roller or platen 3, which carries the paper or other material upon which the writing is done.
The invention contemplates the use of a very

long ribbon which is kept uniformly inked and which moves freely from spool to spool with light type-bar action, light key action and light carriage return at all times.

Conventional portions of the typing machine, not elements of the invention, have been omitted from the drawings as not needed.

Ribbon spools 6 at opposite sides of the front of the frame are provided at the center of hubs 7, with sockets 8 to receive spindles 9 projecting upwardly from hubs 10 of gears 11. Each gear 11 is rotatably mounted upon the head 12 (see Fig. 9) at the inner end of a pivoted arm or lever 13 which is pivotally mounted by a stud 14 and extends diagonally of the frame with its front end projecting forwardly therefrom so that it may be grasped and the lever swung about its pivot and thus move the gear into or out of mesh with a companion gear or small pinion 15, mounted upon the upper end of a drive shaft 16. The shafts 16 are the shafts customarily employed for carrying the spools of a typing machine. Since the gears 11 are a great deal larger than gears 15, spools 6 will turn much slower. A pin 17 projects upwardly from the hub of each gear for engagement in a socket 18 in the spool applied to spindle 9, resting upon hub 7. Therefore the spool will turn with the gear and turn slowly when gear 11 is in mesh with companion gear 15. The gear 11 may be mounted by ball bearings in the head 12 of arm 13 so that when it is swung about its pivot to move the gear 11 out of mesh with gear 15, the spool 6 may turn very freely and thus reduce the drag and tension upon the ribbon to a minimum. Very rapid operation of the typewriting machine with very light touch and easy, quick carriage return are accomplished even with a ribbon 288 yds. long. A shield 19 formed of sheet metal protects each spool. The shield prevents the spool from being accidentally struck when moving the carriage during use of the typewriting machine. Since the shields are releasably secured by screws 20 passed through depending front and side portions of the shields and into threaded openings formed in the frame 2, the shields may be removed when necessary.

When the ribbon has travelled in one direction for its full length it is necessary to swing the arms 13 to adjusted positions and thus cause the previously power driven spool to be free from any connection with the rotating shafts upon which the gears 15 are mounted. The other spool 6 is caused to be driven from the companion gear. It is also necessary to effect automatic, or manual, adjustment of the mechanism for reversing the drive mechanism of the shafts 16 and thereby cause the directional movement of the ribbon and the driving gears 15 to be reversed. Some typists may object to manually shifting the positions of the spools and the gears. They may depend upon a conventional, automatic mechanism for effecting reversal of directional movement of the ribbon. The gears 11 may be rotatably mounted in ball bearings carried by the blocks 21 shown in Fig. 11 which correspond to the heads 12 and are mounted upon the forwardly projecting arms 22 of brackets 23 through which the shafts 16 are rotatably mounted. This modified construction with gears 11 and 15 always in mesh, is shown in Figs. 10 and 11. If gear 15 is always in mesh with gear 11, when a full spool of ribbon is unwinding and the ribbon passes in contact with inking means to receive ink therefrom, then there is much more drag on the rib-

bon and a much shorter ribbon must be employed or greater power must be had to rotate the shafts 16, when either shaft is driving the gears and winding up the ribbon. One may tighten the carriage drum spring as tightly as possible, which causes a heavy key action and a heavy carriage return and means greater exertion for the typist's hands. In order to secure the desired results for the typist from an extremely large spool of ribbon (up to 288 yds. long) it is necessary to combine the features of the freely moving spool 6 with its gear 11 out of mesh with gear 15 so spool 6 is free from any drag which in the case of the right spool in the conventional typewriter, is considerable, that drag being caused by a shaft underneath the type-bars which rotates and the vertical shaft 16 which rotates in the conventional machine when the right spool is unwinding. Of course the right spool in the conventional machine is mounted where I mount driving gear 15.

During movement of the ribbon 5, ink may be applied to it preferably as it moves away from the vibrator 4 and thus cause the ribbon to be supplied with a thin film of ink which is brought in conventional manner into contact with the paper about the platen producing written impressions which are all of the desired rich color. In order to transfer the ink to the ribbon as the ribbon moves in the direction away from the vibrator 4, there are inking units 24 mounted at opposite sides of vibrator 4 and these are alike.

Each of the inking units has a base 25 which may be formed of a block of plastic material, metal, or other suitable material. It is firmly mounted upon a side wall of the frame 2 by screws 26. A metal plate 27 is mounted upon the base block 25 and projects from the inner end thereof. A block 33 is mounted at the front edge of the inwardly projecting end portion of the plate 27; and at opposite sides of this end portion of the plate are guide rollers 29 and 30 rotatably mounted about posts 31 and 32; the post 31 being carried by said block 33 mounted upon the plate and the post 32 being secured to the plate 27 at the opposite side thereof from the block 33. A bar 34 extends transversely of the outer end portion of the plate 27 and, at its rear end, is pivotally mounted by a screw 35 so that it may be urged inwardly by a spring 36 anchored to the plate 27 and attached to the bar. This bar carries an upstanding shaft 37 about which an ink applying wheel 38, with a knurled, peripheral face is rotatably mounted. On the hard ball of Fig. 12 may be used to apply ink to a face of the ribbon 5. Inking wheel 38, with the knurled face has frictional contact with the ribbon so that as the ribbon moves, the wheel 38 will be rotated and ink on the knurled face of the wheel will be transferred to a face of the ribbon. An arcuate guide, or ribbon retainer, 39, having a shank 40 extends, circumferentially of the wheel, for a portion of the circumference thereof and the shank extends 65 inwardly under the wheel with its inner end secured to the bar 34. The fingers 41 of the guide 39 overlie the upper edge of the rim or margin of the wheel 38 and the arcuate guide will thus serve very effectively to guide the ribbon against the knurled face of the wheel; or flanged inking wheels may be used as in Fig. 14.

Referring to Figs. 1 and 2, it will be seen that the ribbon passes about the outer portion of the inking wheel 38 with portions engaged with the guide rollers 29 and 30 and other portions of the

ribbon passing through slotted posts 42 and 43 projecting up from plate 27.

44 of Fig. 4 is a small lever to which the handle or arm 45 is securely fastened. The lever 44 is pivoted to base plate 27. In order to move the small gear 47 out of mesh with the gear 48, the arm 45 is turned forcing inking wheel 38 out of contact with ink screen 65, thus separating the gears 47 and 48 completely. Hub 46 of inking wheel 38 extends downwardly and carries the small gear or pinion 47 which may be in mesh with large gear 48 to cause gear 48 to turn very slowly when the inking wheel 38 is rotated by the ribbon.

The gear 48 is an element of the mechanism by means of which ink is delivered from reservoir or ink well 49 to the ink applying member 38, which may be a wheel with a knurled peripheral face, or a gear or a hard ball. (For the hard ball see Figs. 12 and 13). (For the gear or wheel with teeth and with flanges, see Figure 14). Gear 48 may be rotatably supported upon a thrust bearing 50 which is carried by the plate 27. Gear 48 supports a shaft 51 which projects upwardly therefrom and passes through the housing 52 of the mechanism. Within this housing the shaft 51 carries a rotary ink feeding and mixing member identified by reference numeral 53 in Fig. 6 as a threaded roller and by reference numeral 53-A in Figs. 12 and 15 as a wheel, gear or disk which may be provided with projecting teeth.

Gear 48 may be driven by gear 15 instead of by gear 47 as is shown in Figs. 4 and 6. See also Fig. 2 wherein gear 15 drives gear 48 through an intermediate gear 15-A. Shaft 16-B which may be supported in any suitable manner on the typing mechanism serves as a mounting for gear 15-A, the teeth of which coact with the teeth of gears 15 and 48. Gear 15 may also drive a spool 6 which has gears for its top and bottom as shown in Fig. 15 (such spools are commonly used in one of the standard electrical typing machines) or spool 6 may have a gear fastened securely to its lower face in any suitable manner. When spool 6 is unwinding, I find it necessary to shift the lever or arm 13 so that the spool is entirely free from the drag of any connection with gear 15, whether the spool is mounted above gear 11 or has one or both of its faces with projecting teeth for gears, or has a gear securely fastened to its bottom face, and this is particularly necessary when gear 15 may be connected with both gears 11 by which is meant that gear 15 is in mesh with both faces of the spool 6. In other words, whenever spool 6 is itself constructed of two disks which are in reality gears 11 and 11-A (see Fig. 15) then gears 11 and 11-A must be out of mesh before spool 6 begins the unwind. This is when the typing machine is equipped also with the inking means for feeding ink to the ribbon 5. If the machine is used with very large spools and is not equipped with inking units and the ribbon is removed from the machine for reinking, then it is quite reasonable to employ still larger spools and employ very long ribbons in such machines, just as long as the available space will accommodate, and this means also using spools which reach over and completely cover the gear 15 fastened to shaft 16, and it means using spools that almost touch the platen or roller 3 and which extend two or three inches beyond the sides of the typing machine and extend to the very front of the machine. A gear train may be used.

Ink is moved and stirred and mixed in the ink reservoir automatically during operation of the typing machine and when a threaded inking

roller is employed as may be advisable in certain types of typing machines (see 53 of Fig. 6) the ink is moved to an opening 58 and enters the housing. Cork washers 55 and 56, which may be cork or any suitable material, are located at the upper and at the lower ends of the housing 52 and may be located in between as in Fig. 12 at 56-A. In order to avoid undue leakage of ink when a very thin pigment ink is employed, instead of using the drainage pan of U. S. Patent No. 2,158,944, I use a packing on both sides of cork washer 56. This packing 57 is fitted closely and snugly about the shaft 51. In addition to the regular commercial gaskets or packing, I may also use washers made of closely woven nylon. As the nylon threads are non-ink-absorptive, they serve well for this purpose; particularly if six or eight of them are used. The ink enters the housing 52 from the reservoir 49 through an inlet recess 58 formed at the rear of washer 55, at the rear of the upper part of the housing and at the bottom of the reservoir 49. (See Figs. 5, 6, and 8.) Since the ink must be stirred and mixed, if it is a suitable ink for use in typing machine ribbons for permanent records and for writing letters and documents of importance which require first class, permanent inks, there has been provided an ink mixer or agitator 59 (see Fig. 5) which is secured to the upper end of the internally threaded shaft 51 by screw 60. Since the hub, or enlarged portion of the mixer blade overlies the upper washer 55, it serves to prevent this washer 55 from moving out of its place.

The ink reservoir 49 is supported over the plate 27 and the gear wheel 48 by a post 61 secured upon the plate by a screw 62. About the upper end of this post 61 is groove 63 in which there is a helical spring 64. End portions of this spring 64 extend from opposite sides of the post 61 towards the housing as shown in Fig. 7, and are attached to the ends of a screen 65 which is woven of very fine wire strands or wire threads and extends about the housing with its intermediate portion crossing the discharge opening as shown in Figures 7 and 8. The ink passes through the fine screen and upon the knurled edge face of the inking wheel 38; and from this wheel the ink is transferred to a face of the ribbon 5 as the ribbon moves to the spool. When it is necessary to replenish the supply of ink in the reservoir the cap 66 is unscrewed from the filling opening 67 of the reservoir and ink poured into the reservoir.

Instead of forming the ink feeder in the housing as a threaded roller 53 as in Fig. 6, it may consist of a wheel, gear or a disk 53-A (see Figs. 8, 12 and 15) and formed about its periphery with teeth 69 which serves as an ink feeder and mixer. The disk or gear has an upstanding sleeve 70 which fits about the shaft 51 and is spaced from the annular wall of the housing 52 so that there will be ample room for ink to flow downwardly through the opening at the rear of housing and into contact with the toothed disk.

A typing machine constructed as illustrated and described is very efficient in operation since the ink is fed through the housing from the reservoir with precision at a steady rate of flow to the ink feeder and mixer in the housing and therefrom to the ink applying wheel 38 (see Fig. 6) or to the hard ball 38-A (see Figs. 12, 13 and 15); and by contact the ink is fed to a face of the ribbon in minute amounts; and the power required to do this is much less than in prior mechanisms of my patents and a much longer ribbon may be employed and a ribbon may be used which is made

of synthetic threads which is much more wear resistant than all other ribbons heretofore patented or used for typing machine ribbons with which to do writing on a surface. It is extremely thin and the threads are absolutely uniform in size throughout the entire ribbon even if a ribbon 288 yds. long is employed, since the threads are made mechanically and are composed of artificial fibres. It is well known that cotton threads and spun silk threads are made of short fibres and cannot run perfectly uniform in size and that long fibre silk threads are naturally full of gum and this gum has to be boiled out of the long fibre silk fibres before the usual commercial, silk typewriter ribbon may be produced. The fibres themselves may not be imperfect as to size but the degumming process may not be done perfectly resulting in a ribbon that is not absolutely uniform. It has never been possible to weave natural silk threads at the mill with absolutely perfect results because silk is greatly affected by the temperature of the weaving room, the moisture in the air of the weaving room and by other factors. With synthetic fibres such as I employ for my new, improved typing machine ribbon, there are no such obstacles to securing ribbons of uniform size throughout a 288 yard length and the new threads wear almost like metal threads. The resultant writing from the new ribbon and the very long ribbon and from the use of the new, easier moving inking units, is what typists require. With the very long ribbon they may have writing with the right amount of ink for sharp impressions of rich color and may have such writing for the life of the typing machine without changing the ribbon. It is simply a matter of having the necessary space for the inking units and for the very large spools and in some of the standard typing machine now on the market, there is sufficient space for very long ribbons. By friction calendering, the thickness of the new, synthetic ribbon of this application, may be reduced to as low as .0015 of an inch. When such a ribbon is employed the typist may reasonably use micro type for correspondence and for legal documents since the writing is printlike and as easily read as the printed page of a magazine or book employing usual size type. The new ribbon as thin as .0015 of an inch is extremely tough and wear resistant due to the very unique strength of the synthetic threads. The life of the new ribbon may be prolonged by a fourth by simply using metal type faces which have a dull, knife edge and not a cutting edge. Present typing machines are usually built for use with ordinary cotton writing ribbons as much as .005 of an inch thick and because of this thickness, the type employed, having to write under the great handicap of the heavy, thick, cotton ribbon, have edges that are sharp and that can cut. The cotton fabric is protected to some extent in machines that employ anvils or stop-rings. The new synthetic ribbon can easily withstand the cutting blows of the sharp faced metal type but the writing will be just as beautiful and there will be 25% more of it before the fabric of the synthetic ribbon is badly worn, if the edges of the metal type are dull.

If the ribbon is .0015 of an inch thick, a surprisingly long ribbon may be wound into a ribbon spool and 288 yards of such ribbon does not require a very large spool, that is unwieldy at all. The distance from the platen or roller to the front part of a typing machine which employs spools containing 288 yds. of such a thin synthetic ribbon, is not great and is not at all unreasonable and for the first time, it permits

the use of ribbons and spools and inking units that give the typist what has been greatly needed and it puts an end to the great expense of purchasing so many standard length typing machine ribbons on small spools. These ribbons have ten times the life if ink is fed to them, short as they are, but the custom is to discard the fabric the moment the ink is nearly gone. Each separate ribbon means another metal spool and another box to pay for and the labor expense involved too. However, one big item in very busy offices is that with my new 288 yard, synthetic ribbon .0015" in thickness, the typist doesn't lose time changing ribbons; this is one big item of expense because typist's pay is high and the time lost changing the ribbon and cleaning the hands afterwards is considerable and delays the typist's work. If the writing that is being done is one long document, it means a complete change in the appearance of the writing when the new ribbon is first used. All this is avoided by the use of the combination of the new ribbon 288 yards long, the new, large spools and new spooling gears and the new means for freeing the unwinding spool from any connection with the rotating shafts, and the new, small, freely operating inking units.

One who knows nothing about the typewriter art may say that the spool of the conventional typing machine rotates freely when unwinding but the fact remains that the drag greatly limits the length of ribbon that may be used in connection with the inking units, and it is wholly unnecessary to have the unwinding spool mounted on a rotating shaft especially since the conventional machine has the said shaft connected by gears with a long shaft which extends underneath the typebars across to the opposite side of the machine and both of these shafts rotate in the conventional machine whenever the spool of ribbon unwinds. The drag and tension on the ribbon in such a machine increases as the ribbon in the unwinding spool becomes less. Before making the present invention, applicant visited various typing machine factories of this country and foreign countries and it was impossible to locate any typing machine which did not have the drawback above-mentioned. Applicant experienced great difficulty in using conventional machines, including the electric typing machines, because of the drag on the ribbon and because this drag became much greater if the ribbon was as much as thirty six yards in length. Applicant has observed various types of electrically operated typing machines run night and day, with no manual typing, in making tests of inked ribbons and inking units through the years. This drag which seems of no consequence to the layman is really of great importance and has been a supreme obstacle in securing the results that typists are entitled to have when using typing machines. Business men are entitled to the better writing of the present invention at the large saving in expense for typing machine ribbons. They are entitled to the large amount of writing to be had even in using present typing machines of a few different brands or makes, if the new inventions are attached, as there is the space available for very long inked ribbons and the larger spools and also inking units, although, of course, these machines cannot use 288 yard ribbons for letter writing and for usual office work as the machines are built with a limited space available between the platens and front part.

Through the years business men pay almost as much for inked ribbons for typing machines during the life of such machines as the cost of the machines themselves. The present invention saves this expense and it will only be necessary to purchase ink. Even cotton typing machine ribbons are expensive now. The fabric used for such ribbons must be free from defects which would not matter if the fabric was to be used for making wearing apparel. The inspection of such textile fabrics is very severe since the ribbons must be suitable for use in writing with elite or pica type and any knots or broken threads or other defects can spoil the writing and give a blot or blurred imprint on the writing surface or paper. The cost of weaving cotton fabrics or silk fabrics for inked ribbons is very much higher than heretofore and it is also necessary to pay higher prices for metal spools, wrapping foil, and metal boxes for the ribbons. It is customary for the typist to throw away the spool and the box as well as the used ribbon. The present invention prevents this.

A late model typing machine will do very ugly writing if a very thick, heavily inked ribbon is used. Even a very old typing machine that is in good repair will do very neat work for a long period if given a ribbon 288 yards long that is only .0015 of an inch thick. The typing machine maker, however, purposely limits the space that is available for the ribbon so as to require the frequent replacement of a short ribbon. The writing results from the long ribbon are vastly superior to those obtained from the usual 12 yd. ribbon. Since the 12 yd. ribbon must act as an ink reservoir and carry a reserve ink supply, it writes too heavily at the start, unless it is a lightly inked ribbon, and on the wear down, the writing soon is dim. Not one typist in ten thousand in a busy office is furnished lightly inked ribbons because they contain so little ink and must so soon be replaced. The amount of writing they can do is very little. It is customary for a typing machine salesman to demonstrate a typing machine, of any kind, with a lightly inked ribbon so that the writing will look very sharp and neat. This is misleading because the moment that machine is equipped with the usual cotton ribbon medium inked or heavily inked (for economy) the writing is ugly. The present invention means a great saving in ink used since the extremely thin, non-ink-absorptive, synthetic ribbon gives very sharp writing and very little ink is used in making each impression on the paper. Since the new ribbon makes it reasonable to use micro type in typing machines for general correspondence and for legal documents, it is possible to put twice as much on a page as when pica type is used. Paper also is very expensive today and this means a big saving.

The twelve yard, standard, typing machine ribbon is commonly used in typewriters, teletype machines, bookkeeping machines, etc. It is common to see court stenographer's transcripts written with several ribbons and with writing of very different ink color at different places in the large, thick books of court testimony. It is common to see loose leaf records of the auditing departments of hotels and business offices and also bank records with different looking imprints on the sheets. One line may be lightly inked writing and the next line (when new ribbon was used) may be heavy.

The present invention remedies these defects once and for all.

There is no longer any reason why the higher courts should require that all court papers of a case the judges are to read must be printed since with the new .0015 of an inch synthetic ribbon the writing from the typing machine equipped with the inking units is printlike and for thousands of pages remains of the same rich color, and at little expense by an inexpensive process photo-stat copies may be produced which are just as easily read as actual printed pages.

Since the new very thin, synthetic ribbon is non-ink-absorbent it is cleaner than prior art ribbons and when used with the inking units (which feed minute amounts of ink during operation of machine) the synthetic ribbon simply carries a small amount of surface ink and there is very little ink for the type to strike into and it is seldom necessary to clean the type of the machine of the present invention. This type of ribbon is especially valuable in using the micro type and due to its thinness it gives the full beauty of the micro type faces and makes them very easy to read. Usual standard ribbons are not satisfactory for use with the micro type because of the reserve ink supply they all must carry which mean thickness of fabric and ugly outlines from micro type. Much more use of the fabric may be had from a micro type machine since the micro type are so small they strike a very small portion of the width of the ribbon. In my U. S. Patent No. 1,324,265, is shown a mechanism for making different parts of the width of the ribbon usable so that the entire width of the fabric will be utilized and none wasted. Even with a writing ribbon only $\frac{1}{16}$ of an inch wide, it is possible to write along three different paths of the ribbon when using a typing machine equipped with micro type. And micro type is a standard type of typing machine makers and has been for long years. The ink fountain typewriter makes such type of high importance.

One form of an ink applying wheel which may be used is simply a gear 38 of approximately one-fourth inch in diameter and with a periphery approximately $\frac{3}{2}$ of an inch thick; or another form is shown at 38—A of Fig. 12 and also at 38—A in Fig. 13. The hard ball 38—A carries a small gear and this gear is driven by the rotary member 53—A. For each revolution of rotary member 53—A, the member 38—A may make a large number of revolutions. The ribbon may be held in yielding contact with rotary member 38—A by means of a post 74 as shown in Fig. 15. This post may have a flat surface 78 on the side which contacts the ribbon and presses it yieldingly against rotary member 38—A. As best shown in Fig. 16 within post 74 and directly opposite the ribbon and directly opposite the rotary member 38—A is first a metal pin 77 with a smooth, flat surface 78 pressing against the ribbon and pressing the ribbon against rotary member 38—A. Back of the pin is a spring 76 of suitable resiliency which maintains the metal pin 77 pressing against a face of said ribbon and pressing the said ribbon yieldingly against the rotary member 38—A as said member is positively driven by rotary member 53—A. Gear 15 is mounted on shaft 16 and gear 48 is positively driven. Gear 15 may drive a gear train of which 48 is one member and gear 11 of a spool 6 may be another member. I do not limit the number of gears which may be driven by the gear 15.

Ribbon 5 of Fig. 13 may be pressed yieldingly

against the ball 38—A of Fig. 13 as above described and as illustrated in Fig. 15 by the spring 76 and metal pin 77 within post 74. The spring may be of any suitable diameter. I prefer that the pin be at least one-eighth of an inch in diameter and have a smooth, polished face 78 against the ribbon and directly opposite the rotary member 38—A of Fig. 13.

Another form of ink applying member is shown in Fig. 14. Wheel 71 may be used instead of the other ink applying members shown in the other figures of the application. This wheel has shaft 37—A and shaft 37—A carries gear 47—A. About the periphery of wheel 71 are the flanges 72 which serve to hold the ribbon in place and are employed in place of the guide 39 shown in Fig. 4. A circumferentially extending rib 73 of any desired shape may project from the wheel 71 about the periphery thereof for engagement with the ink on the surface of screen 65—A. This rib may be knurled or formed with small teeth for good frictional contact with a face of ribbon 5. The projecting rib 73 of wheel 71 may have a perfectly smooth surface that may be one-eighth inch wide, or wider, or narrower, and wheel 71 may be positively driven from gear 15 on shaft 16, since the smooth surface of the rib will not furnish good frictional contact with ribbon 5. Or I may use a small, hard, rotating ball instead of wheel 71, mounted on a small shaft 37—A carrying the gear 47—A. The ball may be $\frac{1}{2}$ of an inch in diameter or any desired size to meet the inking requirements of the typing machine of which it will be a part, to keep the optimum amount of ink on a face of a writing ribbon for writing of rich color that is at all times neat and printlike. The ball may have a smooth surface and get its ink from contact with the screen's ink supply. The ball may be partly enclosed or it may be entirely outside a housing. It may be driven from gear 15 mounted on shaft 16 as shown in Fig. 12 wherein gear 15 drives gear 48, and rotary member 38—A is not dependent for rotary motion upon the contact it makes with a face of ribbon 5.

Still another form of ink applying member is shown in Fig. 15. Rotary member 38—A is a smooth surface ball which rotates as it presses towards the disk 53—A. Inside post 74 is a horizontal hole extending through the flat face of the post that is towards ball 38—A and said hole goes into the post and almost through it, and said hole is sufficiently long to hold a resilient spring 76 and on top of said spring is a substantial metal pin 77, which may be $\frac{1}{2}$ of an inch in diameter and said pin is pressed by said spring yieldingly towards the ball 38—A and presses ribbon 5 against said ball yieldingly and presses said ball yieldingly towards disk 53—A. Disk 53—A may have teeth of any desirable size or it may be smooth. Shaft 51—A carries gear 48 and also disk 53—A. Shaft 51 also carries ink mixer and thinner 59—A. The cork washers 55—A and 56—A lie above and below disk 53—A within housing 79. The ball 38—A is almost completely enclosed by housing 79. Spool 6 may have gears 11 and 11—A for its two faces and spool 6 may be in mesh with gear 15—A mounted on shaft 16. Gear 15 may also be in mesh with gear 48 for rotation of disk 53—A and ink mixer and thinner 59—A. Spool 6 may be supported as shown in Fig. 9 but omitting the teeth of gear 11 since spool 6 of Fig. 15 has gears for its top and for its bottom faces.

The ink applying members of Figs. 12, 13 and

15 are particularly for typing machines now conventional and where the space is extremely limited for attaching inking units and larger spools. The spools used may have gears for their top and bottom sides or they may have one gear each as one side of a spool, or a gear may be fastened to a face of a spool as may be desirable for the machine. When inking mechanisms are employed such as illustrated in Figs. 12, 13 and 15, there is a considerable saving in making the same as fewer parts are required than for the mechanisms of Figs. 1, 4, 5, 6, 7 and 8. The mechanism of Fig. 14 is simpler and has fewer parts than the mechanisms of Figs. 1, 4, 5, 6, 7 and 8.

After several years use of the typing machine of U. S. Patent 2,322,737 I find it gives good results but it is much more costly today to rebuild present conventional typing machines and equip the same with the new shafts and gears and axles and large spools of the machine of that patent than it is to equip conventional typing machines with the present invention. The inking units of the present invention are much smaller and operate more easily and more efficiently and the spools of the present typing machine may be larger and carry more ribbon and much wider ribbon than the machine of the Patent 2,322,737. The typist may write very rapidly with the machine of the present invention using much larger spools than spools of the invention of said patent and expend less energy at all times. This is due to the fact that the present invention uses the ribbon of great length more efficiently and with less drag than heretofore. The carriage spring carried in drum 100 of said patent (see 100, Fig. 1, sheet 1 of said patent) must be made tighter when using the machine of said patent than is necessary in using the present invention. As that spring is tightened, the force necessary to move the typebars is increased and the typist finds it necessary to put more energy into the movement of each of the keys of the typing machine. The ideal typing machine has the lightest, quickest, snappiest and most elastic and satisfying action and it gives neat, printlike writing at all times from one ribbon which during the life of the machine never wears out because the fabric is tougher than other fabrics used in typing machines and is longer and is always inked. When a ribbon becomes dry, the type injure the fabric much faster.

It will, of course, be understood that the mechanisms described may be used on any typing or printing mechanisms employing type and a transfer member, whether said member is in the form of a ribbon, sheet or any other form.

The hard ball of Figs. 12, 13 and 15 may be of plastic, metal, stone, or any suitable material.

I do not limit myself as to the kinds of material used for any of the various parts of the invention. While screens are illustrated and described, these are not a necessity for all typing machines. Also it is to be understood that the constructions shown are for purposes of illustration only and variations may be made in sizes and styles of parts and in details without departing from the scope of the present invention in any way.

I may use a synthetic ribbon made of chemical fibres, that is man-made fibres which may be a protein-like chemical product or polyamide. The superpolymers which make up the polyamide family can be made in several different ways. One of the simplest involves the reaction of a dibasic acid (of which there are many) with an organic

diamine. This reaction, which results in the formation of relatively small molecules, is followed by heating to bring about the union of many of these small molecules to give the giant polyamide molecules. Thousands of different chemical fibres can be made by interpolymerization of various dibasic acids, amino-acids, and diamines. Dibasic acids derived from phenol may be used in making chemical fibres suitable for the threads of non-ink-absorbent typing machine ribbons; also a diamine likewise derived from phenol may be used. Oxygen from the air is also needed in making the dibasic acid, and ammonia is used in making the diamine. Drawn, synthetic fibres of this chemical nature possess a high degree of elasticity and also have great tensile strength and great wear resistance under the blows of the metal type of machines used in writing. While the expression "non-ink-absorbent" is used in this application, I do not limit the writing ribbon to wholly non-ink-absorbent fibers and do not limit myself to synthetic fibres. I may use a ribbon that has synthetic fibres in the warp and has natural fibres of cotton or silk in the filling, or vice versa. Metal fibres that are 25 rustproof and that are very pliable and are extremely fine in size may be used either in warp or filling. Such fibres are now a commercial product available to the public, very closely woven in extremely thin, very smooth fabrics. Or I may use synthetic ribbons made in part (or entirely) under the viscose, cuprammonium, nitrocellulose or other processes. Or I may use silk fabric containing all or part of the natural gum and such fabric may be highly calendered to an extremely 30 thin ribbon that is substantially non-ink-absorbent. Or I may use natural cotton fibers which have not been chemically treated to clean them and make them ink absorbent as is usually done when making inked ribbon fabric. The ink inlet 35 58 at the rear of the housing may be entirely outside the cork washers and may be an inlet formed by cutting away a portion of the wall of the housing. The ink inlet may be of any suitable size for feeding the amount of ink that is required in the particular inking mechanism for supplying ink correctly to the ribbon. The ink feeding and mixing members 53 and 53—A may be of any size needed for feeding the correct amount of ink required for micro type, elite type, pica type, small gothic type, bulletin type, roman type, etc.

For teletype machines, I may use a non-pigment ink in the reservoir and may use a plain disk, having a smooth peripheral surface, as the ink feeder, since the one ink mixer in the reservoir is usually sufficient for such a thin ink; or I may omit the ink feeding disk and use a wool or cotton wick or wool yarn for feeding an extremely thin ink to the ink applying member which is in actual contact with a face of the writing ribbon.

This application is being written with the new writing ribbon of my invention mounted in the ink fountain typewriter of Fig. 1. The spools are much larger than normal and are mounted as shown in Figs. 9 and 10. The spools are mounted near the conventional shafts used ordinarily in all typewriters for carrying the spools. The shafts in the ink fountain typewriter which is being used are carrying no spools but carry steel gears of the type shown as 15 in Fig. 10. Directly underneath the spools are the large gears 11. When winding the ribbon, gears 15 and 11 are in mesh. When the spool is full of ribbon and begins to unwind, it is entirely free from any con-

nection whatever with gear 15. The spool completely hides gears 11 and 15. The winding spool always moves much slower than the gear 15 when gears of relative sizes shown in Fig. 10 are used in the typing machine. I may use fabric screens behind the thin, wire screens. I may use pigment ink of the type commonly used in pigment ink ribbons. For more details on these subjects, reference is made to U. S. Patents 2,074,969; 2,158,944.

What I claim is:

1. Device for supplying ink to a ribbon in a typing machine during operation of said machine, comprising an ink reservoir; a stationary member and pressure spring on one side of said ribbon; an ink applicer in the form of a ball, on the opposite side of said ribbon; and means for applying ink from said reservoir to said ink applicer for transfer to said ribbon in the desired amounts.
2. In a device for use in a typing machine which employs a writing ribbon composed of synthetic threads having a tensile strength greater than natural fibers, a frame, a base plate, a shaft driven during the operation of the machine having a gear mounted thereon to rotate with said shaft, rotatable supporting means for a ribbon spool including a gear, a movable lever mounted on said base plate which serves as a support for said rotatable supporting means, an inking mechanism having at least one rotary member driven by a gear which is permanently in mesh with the aforesaid gear on said shaft, means for attaching said base plate to said frame, and means for moving said lever to effect meshing of said shaft gear and said gear of the rotatable ribbon spool supporting means for winding said ribbon upon said spool and for moving said gears out of meshing relation when the ribbon is unwinding from said spool during operation of the machine.
3. Device for a typing machine employing a writing ribbon, including at least one base plate; spools supported in spaced relation between which said ribbon is transferred during operation of said machine; at least one driving shaft for driving a ribbon spool for winding said ribbon; a movable support for a spool for moving said spool out of any driving connection with said shaft when said ribbon is unwinding from a spool in a typing machine; an inking mechanism, including an ink reservoir; an ink feed member for feeding ink from said reservoir to a rotary ink applicer for transfer to a face of said ribbon; mechanical driving means, independent of said ribbon, for driving said ink applicer positively from said driving shaft; and that spool which is unwinding the said ribbon having a different position in said machine from its position in the machine when said spool is winding the said ribbon; and means for simultaneously breaking the driving connection by which said ink applicer may be free from the driving force of said driving shaft, and said ink applicer may also be free from contact with said ink.
4. In a typing machine having a writing ribbon and a mechanism to make inked impressions on a writing surface by means of said ribbon; means for moving said ribbon past the typing position, including ribbon spools; spool driving shafts fitted with gears; at least one inking mechanism for inking said ribbon, including a reservoir for ink; an inking member receiving ink from said reservoir; a rotary ink applicer having a gear; said inking member having a gear which is adapted to mesh with a gear on said driving

shaft; the said inking member's gear and the said driving shaft gear being constantly in mesh; and means for bringing the gear of said ink applicer in mesh with the gear of said inking member; means for feeding said ink from said inking member to said ink applicer for transfer to a face of said ribbon; said spools being mounted on shiftable supports separate from said spool driving shafts, and said shafts being free from the weight of said spools and of said ribbon when wound into a spool; and that spool which is unwinding the said ribbon having a different position in said machine from its position in the machine when said spool is winding said ribbon; and that spool which is unwinding being entirely free from any connection with said spool driving shaft or any gear fastened to said shaft so that said spool which is unwinding may unwind with much less ribbon tension and drag than in prior art machines and conventional typing machines.

5. In a typing machine having a writing ribbon and a mechanism to make inked impressions on a writing surface by means of said ribbon; means for moving said ribbon past the typing position, including ribbon spools; spool driving shafts fitted with gears; at least one spool being mounted separate and apart from said spool driving shafts, on a shiftable base; both of said spool driving shafts being free from the weight of any spools at all times; at least one inking mechanism for inking said ribbon, including a reservoir for ink; a housing extending from said reservoir; a threaded, rotary member within said housing an opening in said housing for passage of ink from said rotary member to a flanged inking wheel; said rotary member having a gear which is in constant mesh with a gear which is in driving connection with said spool driving shaft; means for driving said wheel; means for forcing said wheel out of driving connection with any other rotary member of said inking mechanism and at the same time forcing said wheel away from any contact with ink from said rotary member; and said ribbon contacting said wheel for transfer of ink therefrom to a face of said ribbon; and that spool which is unwinding the said ribbon having a different location in said machine from its location when winding said ribbon.

6. A device for use in a typing machine employing a writing ribbon and having spools supported in spaced relation between which said ribbon is transferred during operation of the machine, said device comprising at least one inking mechanism having at least one rotary member for applying ink to said ribbon; at least one spool driving shaft adapted to support at least one gear; means for connecting a spool with said driving shaft to rotate said spool when said ribbon is being wound; means for connecting said rotary member of said inking mechanism with said driving shaft entirely independent of the movement of said ribbon; and means for breaking the driving connection between the said shaft and the said spool and also between the shaft and the said rotary member.

7. A device for use as a part of a typing machine employing vertical spool shafts, including ribbon spools mounted on movable bases positioned in spaced relation to said spool shafts, a ribbon which is transferred between said spools during operation of said machine, at least one inking mechanism having at least one ink reservoir, and at least one ink feed roller and at least one ink applicer which rotates as it receives ink

fed to it from said reservoir by said roller, and as it applies ink to a face of said ribbon; means for driving the rotating members of said inking mechanism from at least one of said spool shafts, and means for breaking the driving connection between said shaft and at least one of said rotating members.

8. Device for use as a part of a typing machine employing a writing ribbon and employing means for making inked impressions on a surface; said device including a ribbon spool and at least one inking mechanism having at least one rotary member; means for driving said rotary member independent of the said ribbon; a driving shaft adapted to rotate said rotary member of said inking mechanism; said driving shaft being also adapted to rotate said ribbon spool; and means for breaking the driving connection between said shaft and said spool and between said shaft and said rotary member when said spool is unwinding.

9. In a typing machine having a writing ribbon and a mechanism for making inked impressions on a surface by means of said ribbon; means for moving said ribbon past the typing position, including spools, spool shafts; gears for connecting said spools and shafts; a mechanism for inking said ribbon; said mechanism including a reservoir for ink and at least one rotary member; means for driving said rotary member from said shaft independent of said ribbon; means for rotating said spool by said shaft when said ribbon is winding into said spool; and means for freeing said spool from any connection with said driving shaft when said ribbon is ready for unwinding from said spool.

10. In a typing machine having a writing ribbon and a mechanism for making inked impressions on a surface by means of said ribbon; means for moving said ribbon past the typing position, including spools, spool shafts; driving means for connecting said spools and shafts; and a mechanism for inking said ribbon, said mechanism having at least two rotary members; means, independent of the movement of said ribbon, for driving at least one of said rotary members from said shaft; and means for freeing a spool from any connection with said driving shaft when said ribbon is ready to unwind from a spool.

11. In a typing machine having a writing ribbon and means for making impressions on a writing surface, the combination of means for moving said ribbon past the typing position, including spools, spool driving shafts, with a mechanism for inking said ribbon; said mechanism having at least one rotary member; and driving means, independent of said ribbon, connecting said rotary member and said shaft; and means for breaking the driving connection between said driving shaft and said rotary member; and means for separating said driving shaft from connection with said spool when said ribbon is ready to unwind therefrom.

12. In a typing machine, the combination of a writing ribbon including synthetic, substantially non-ink-absorbent, fibres of greater strength than natural textile fibres, a ribbon spool on which said ribbon is adapted to be wound and unwound and an inking mechanism including at least one rotary member, for feeding ink to said ribbon in said machine; a spool rotating shaft connected with a rotary member of said inking mechanism for rotating said member; and means for breaking the driving connection between said shaft and said rotary member when said ribbon is ready to unwind from said spool.

13. In a typing machine equipped with a writing ribbon, including at least some synthetic fibres of greater strength and wear resistance under the blows of the type of said machine than natural textile fibres, the combination of an ink reservoir and means for feeding ink from said reservoir to a face of said ribbon in said machine during operation of same; said means including at least two rotary members; a spool rotating shaft; a spool for winding said ribbon; driving means for driving at least one rotary member of said means for feeding ink, from said shaft, independent of the said ribbon; and means for instantly breaking the said driving connection between said shaft and said rotary member.

14. In a typing mechanism for printing impressions upon a surface which employs an ink carrying ribbon that is moved between spools during the operation thereof, the combination comprising shaft means driven during the operation of said mechanism, an ink reservoir, rotary means in contact with said ribbon for transferring ink from said reservoir to said ribbon, means for driving said rotary means by said shaft means, means for rotatably supporting a ribbon spool, driving means for rotating said ribbon spool by said shaft means, and means for selectively disengaging said driving means between said shaft means and said ribbon spool.

15. In a typing mechanism for printing characters upon a surface, wherein is employed an ink carrying ribbon that is transferred between spools during the operation thereof, the combination comprising a gear fixedly mounted on a shaft which is driven during the operation of said mechanism, an ink reservoir, rotary means in contact with said ribbon for transferring ink from said reservoir to said ribbon, means for driving said rotary means from said gear, a ribbon spool rotatably supported by said mechanism, a driving connection for positively driving said ribbon spool by said gear, and means for rendering inoperative said driving connection between said gear and said ribbon spool.

16. In a typing mechanism for printing impressions upon a surface which employs an ink carrying ribbon that is transferred between spools during the operation thereof, the combination comprising a gear fixedly mounted on a shaft which is driven during the operation of said mechanism, an ink reservoir, rotary means in contact with said ribbon for transferring ink from said reservoir to said ribbon, a ribbon spool rotatably mounted upon a movable support, a driving connection for positively driving said ribbon spool from said gear, and means for moving said movable support and said ribbon spool to render inoperative the driving connection between said ribbon spool and said gear.

17. In a typing mechanism employing an ink carrying ribbon for printing characters upon a surface, a frame for said mechanism, spools supported in spaced relation between which said ribbon is transferred during operation of said mechanism, rotatable supporting means for each of said spools supported on said frame, shaft means driven during the operation of said typing mechanism, a ribbon inking mechanism comprising an ink containing enclosure having an opening therein, an ink distributing device positioned within said enclosure and mounted for rotatable movement to control the movement of ink to the opening of said enclosure, and a rotatable inking member mounted to contact with a face of said ribbon as it is transferred between spools and

positioned to receive ink at said opening, means to effect a driving connection between said shaft means and the spool upon which the ribbon is being wound, and means to effect a driving connection between said shaft means and the aforesaid rotatable elements of said ribbon inking mechanism.

18. In a typing mechanism employing an ink carrying ribbon for printing characters upon a surface, a frame for said mechanism, spools supported in spaced relation between which said ribbon is transferred during operation of said mechanism, rotatable supporting means for said spools supported by said frame, a first shaft having a gear mounted thereon which is driven during the operation of said mechanism, a ribbon inking mechanism comprising an ink containing enclosure having an opening therein, an ink distributing device positioned within said enclosure and mounted upon a second shaft for rotatable movement to control the supply of ink to the opening of said enclosure, a gear secured to said second shaft positioned in meshing relation with the gear on said first shaft, a rotatable inking member mounted to contact with a face of said ribbon as it is transferred between spools and positioned to receive ink supplied to said opening, means to effect a driving connection between said gear on the first shaft and the spool upon which said ribbon is being wound, and gear means for effecting a driving connection between said ink distributing device and said rotatable inking member.

19. In a typing mechanism employing an ink carrying ribbon for printing characters upon a surface, a frame for said mechanism, spools supported in spaced relation between which said ribbon is transferred during operation of the said mechanism, rotatable supporting means for said spools supported by said frame, a shaft driven during the operation of said mechanism, a ribbon inking mechanism comprising an ink containing enclosure having an opening therein, an ink distributing device positioned within said enclosure and mounted for rotatable movement to supply ink in precise amount desired to the opening of said enclosure, means to effect a driving connection between said shaft and said ink distributing device, a rotatable inking member mounted to contact with a face of the ribbon during its transfer between spools and positioned to receive ink at said opening, and means to effect a driving connection between said ink distributing device and said rotatable inking member.

20. In a typing mechanism employing an ink carrying ribbon for printing characters upon a surface, a frame for said mechanism, spools supported in spaced relation between which said ribbon is transferred during operation of said mechanism, rotatable supporting means for said spools supported by said frame, a first shaft having a gear mounted thereon which is driven during the operation of said mechanism, a ribbon inking mechanism comprising an ink containing enclosure having an opening therein, an ink distributing device positioned within said enclosure and mounted upon a second shaft for rotatable movement to supply ink to the opening of said enclosure, a gear secured to said second shaft upon which said ink distributing device is mounted and positioned in meshing relation with said gear on said first shaft, a rotatable inking member mounted to contact with a face of said ribbon as it is transferred between spools and posi-

tioned to receive ink supplied to said opening, and means to effect a driving connection between said ink distributing device and said rotatable inking member.

21. In a typing mechanism for printing characters upon a surface employing an ink carrying ribbon, spools mounted on said mechanism in spaced relation between which said ribbon is transferred, shaft means driven during operation of said typing mechanism, an ink containing enclosure having an opening therein, an ink distributing device positioned within said enclosure and mounted for rotatable movement to control the amount of ink supplied to the opening of said enclosure, a rotatable inking member mounted to contact with a face of said ribbon as it is transferred between spools and positioned to receive ink supplied to said opening, and means to effect a positive driving connection between said shaft means and said ink distributing device.

22. In a typing mechanism employing an ink carrying ribbon for printing characters upon a surface, a frame for said mechanism, spools supported in spaced relation between which said ribbon is transferred during operation of said mechanism, rotatable supporting means for said spools supported by said frame, a ribbon inking mechanism comprising, an ink containing enclosure having an opening therein, an ink distributing device positioned within said enclosure and mounted upon a first shaft for rotatable movement to control the ink supplied to the opening of said enclosure, a gear mounted upon said first shaft, a rotatable inking member mounted to contact with a face of the ribbon as it is transferred between spools and positioned to receive ink supplied to said opening in said enclosure, supporting means for said rotatable inking member comprising a second shaft which is driven during the operation of said mechanism, and means for effecting a driving connection between said second shaft and the gear mounted upon said first shaft.

23. In a typing mechanism employing an ink carrying ribbon for printing characters upon a surface, first and second spools supported in spaced relation between which said ribbon is transferred during operation of said mechanism, spindles for supporting each of said spools, pivoted supporting members for said spindles, shaft means driven during the operation of said typing mechanism, coupling means for effecting a driving connection between said shaft means and a first spool upon which said ribbon is being wound, and means for moving said pivoted supporting member to shift the position of the spindle and first spool when the ribbon unwinds from said spool thereby disengaging said coupling means.

24. In a typing mechanism employing an ink carrying ribbon for printing characters upon a surface, a frame for said mechanism, spools supported in spaced relation between which said ribbon is transferred during operation of said mechanism, rotatable supporting means for each of said spools supported by said frame, shaft means driven during the operation of said typing mechanism, coupling means for effecting a driving connection between said shaft and one of said spools, means for selectively disengaging said coupling means, a ribbon inking mechanism comprising an ink containing enclosure having an opening therein, an ink distributing device positioned within said enclosure and mounted for rotatable movement to control the

amount of ink supplied to the opening of said enclosure, a rotatable inking member mounted to contact with a face of said ribbon as it is transferred between spools and positioned to receive ink supplied to said opening, and means to effect a driving connection between said shaft means and the aforesaid rotatable elements of said ribbon inking mechanism.

25. In a typing mechanism employing an ink carrying ribbon for printing characters upon a surface, a frame for said mechanism, a first and second spool supported in spaced relation between which said ribbon is transferred during operation of said mechanism, spindles for supporting each of said spools, pivoted supporting members for said spindles, shaft means driven during the operation of said typing mechanism, coupling means for effecting a driving connection between said shaft means and a first spool upon which said ribbon is being wound, means for moving said pivoted supporting member to shift the position of the spindle and first spool when the ribbon unwinds from said spool thereby disengaging said coupling means, a ribbon inking mechanism comprising an ink containing enclosure having an opening therein, an ink distributing device positioned within said enclosure and mounted for rotatable movement to control the amount of ink supplied to the opening of said enclosure, a rotatable inking member mounted to contact with a face of said ribbon as it is transferred between spools and positioned to receive ink supplied to said opening, and means to effect a driving connection between said shaft means and the aforesaid rotatable elements of said ribbon inking mechanism.

26. In a typing mechanism employing an ink carrying ribbon for printing characters upon a surface, a frame for said mechanism, spools supported in spaced relation between which said ribbon is transferred during operation of said mechanism, rotatable supporting means for each of said spools supported by said frame, shaft means driven during the operation of said typing mechanism, coupling means for effecting a driving connection between said shaft and one of said spools, means for selectively disengaging said coupling means, a ribbon inking mechanism comprising an ink containing enclosure having an opening therein, an ink distributing device positioned within said enclosure and mounted for rotatable movement to control the amount of ink supplied to the opening of said enclosure, a rotatable inking member mounted to be rotated by frictional contact with a face of said ribbon as it is transferred between spools and positioned to receive ink supplied to said opening, and means to effect a driving connection between said rotatable inking member and said ink distributing device.

27. In a typing mechanism employing an ink carrying ribbon for printing characters upon a surface, a frame for said mechanism, spools supported in spaced relation between which said ribbon is transferred during operation of said mechanism, rotatable supporting means for each of said spools supported by said frame, shaft means driven during the operation of said typing mechanism, coupling means for effecting a driving connection between said shaft and one of said spools, a ribbon inking mechanism comprising an ink containing enclosure having an opening therein, an ink distributing device positioned within said enclosure and mounted for rotatable movement to control the amount of ink supplied

21

to the opening of said enclosure, a rotatable inking member mounted to be rotated by frictional contact with a face of said ribbon as it is transferred between spools and positioned to receive ink supplied to said opening, and means to effect a driving connection between said rotatable inking member and said ink distributing device.

28. In a typing mechanism for printing characters upon a surface employing an ink carrying ribbon, the combination comprising, means for moving said ribbon through the typing position during operation of said mechanism comprising spools mounted in spaced relation between which said ribbon is transferred, an inking means for said ribbon comprising an ink containing enclosure having an opening therein, a rotatable ink distributing device positioned within said enclosure having a circular configuration and provided with elements projecting from the perimeter thereof, said device mounted to control the movement of ink from said enclosure and to said opening, a rotatable inking member substantially spherical in shape mounted to contact with a face of said ribbon as it is transferred between spools and positioned to receive ink at said opening, and means to effect a driving connection between said ink distributing device and said inking member.

29. In a typing mechanism for printing characters upon a surface employing an ink carrying

22

ribbon, the combination comprising, means for moving said ribbon through the typing position during operation of said mechanism comprising spools mounted in spaced relation between which said ribbon is transferred, and inking means for said ribbon comprising a reservoir for ink, a housing in fluid communication with said reservoir, said housing having an opening therein, a threaded roller rotatably mounted within said housing for controlling the movement of said ink from said reservoir to said opening, a rotatable inking member having a surface thereof in contact with said ribbon mounted to receive ink at said opening and to transfer it to said ribbon, as it is moved between spools, and means effecting a driving connection between said threaded roller and said rotatable inking member.
